CLAIM

The ornamental design for “swaddling garment with mesh portion”, as shown and described.

DESCRIPTION

FIG. 1 is a front elevation view of a swaddling garment with mesh portion, showing my new design;

FIG. 2 is a rear view thereof;

FIG. 3 is a top plan view thereof;

FIG. 4 is a bottom plan view thereof;

FIG. 5 is a right side elevation view thereof; and,

FIG. 6 is a left side elevation view thereof.

The pattern sporadically depicted throughout the views is intended to indicate that the pattern is continuous throughout the surface on which the pattern is shown.
